UNITED STATES PATENT OFFICE.

ALBERT E. NEWTON, OF WORCESTER, MASSACHUSETTS.

POWER-TRANSMITTING MECHANISM.

No. 895,102.

Specification of Letters Patent.

Patented Aug. 4, 1908.

Application filed July 7, 1903. Serial No. 164,569.

To all whom it may concern:

Be it known that I, ALBERT E. NEWTON, a citizen of the United States, residing at Worcester, in the county of Worcester and State of Massachusetts, have invented a new and useful Power-Transmitting Mechanism, of which the following is a specification.

This invention relates to a power transmitting mechanism.

10 The object of this invention is to improve the construction of radial drills and the like, and the improvements especially relate to a construction by which the gearing used for driving and feeding the drill-spindle can be 15 conveniently arranged and accurately and economically manufactured.

To this end the invention consists of the parts and combinations hereinafter described and claimed.

20 Referring to the accompanying five sheets of drawings forming part of this application for patent, Figure 1 is a front elevation of the radial arm of a radial drill and the parts mounted thereon, showing how certain features of the invention may be applied thereto. Fig. 2 is a rear elevation of the drill head. Fig. 3 is a side detail view of the reversing gearing looking at the same from the position indicated by the arrow 3 in Fig. 2. Fig. 4 is 25 a sectional view thereof taken on the plane 4-4 of Fig. 3. Fig. 5 is a sectional view through the upright driving shaft and back gearing therefor. Fig. 6 is a detail view of a friction which may be used thereon. Fig. 7 is a detail view of a yoke or arm for controlling the same. Fig. 8 is a plan view showing an arrangement of the centers of the feeding mechanism. Fig. 9 is a sectional view taken on the planes 9-9 of Fig. 8, illustrating the 30 construction of a feeding mechanism. Fig. 40 10 is a top plan view illustrating the construction of the framing shown for carrying the gearing which makes up the feeding mechanism, and Fig. 11 is a front view 45 thereof.

Referring to the drawings, and in detail. A designates the usual upright frame, fitted to slide vertically on which is a base-piece B in which is pivoted the radial arm C.

50 Fitted to slide on the radial arm C is a drill-head D.

A power shaft 10 is arranged concentrically with the pivots of the radial arm, and by means of miter gears drives a shaft 11 journaled in brackets secured to the radial arm. 55 This shaft 11 has a key-way cut in the same,

and said shaft passes through friction clutch hubs 13-13, which have keys engaging said key-way. These friction clutch hubs 13-13 are loosely fitted inside the hubs of bevel gears 14-14. The hubs of these bevel gears 14-14 are loosely journaled in brackets or arms projecting from the drill-head, and are held therein by suitable collars. Each friction clutch hub 13 is arranged with a friction clutch in connection with its respective bevel gear, the details of which friction are herein-after described at length. Fitting loosely on said shaft 11 is a sliding hub 15 which has tapered ends to engage arms projecting from the respective clutches. Engaging a groove cut in said hub 15 is a yoke 16 mounted on a shaft 17 fitted in lugs projecting from the bearings which carry the friction clutch hubs 13-13 and the bevel gears 14-14. The 60 end of said shaft 17 is slabbed and fitted to the same is the end of a lever 18 which is mounted on a suitable pivot carried by the drill-head. By means of this lever 18 either friction clutch can be operated so as to engage its bevel gear 14. By this construction the upright shaft hereinafter referred to can 65 be driven in either direction.

Engaging both bevel gears 14-14 is a bevel gear 19, which is secured on the end of a friction clutch hub 20, which is loosely journaled in a bearing secured to the drill-head. The upper end of this hub is formed into a cup, and loosely fitting into said cup is a friction clutch 21 which is keyed to the upright shaft 22. This friction clutch 21 consists of a hub projecting from which is a circular rib 23, the end of which is cut off so as to be capable of radial movement.

Fitting into depressions so as to engage the 95 fixed part of the hub and the free end of the circular rib are two pins 24-24. The sides of these pins are slabbed where they bear on each other. Projecting from each of these pins is an arm 25, each of which carries a 100 bearing-head 26 at its free end.

Sliding on the upright driving shaft 22 and keyed thereto is a hub 27, the end of which is tapered and fits in between the bearing-heads 26.

When the sliding hub 27 is moved downwards towards the friction, the tapered end of the same forces the arms 25 outwardly, and thereby forces the circular rib radially to engage the hub of the friction clutch, so that the upright shaft 22 will be locked to and will 110 turn with the bevel gear 19.

The same construction of friction clutch is used between the clutch hubs 13—13 and the bevel gears 14—14.

Mounted in a bearing secured to the drill-head is a hub 28 which has clutch teeth 29. The sliding hub 27 has corresponding clutch teeth 30. By sliding the hub 27 upwards, the upright shaft 22 is locked to said hub 28.

Keyed on the hub 20 is a pinion 31, which meshes with a gear 32 mounted on the end of a back-gear shaft 33 which is journaled in a suitable bracket carried by the drill-head. On the upper end of the back gear shaft 33 is arranged a pinion 34 which engages a gear 35 keyed on the hub 28. Keyed on the top of the upright driving shaft 22 is a pinion 36. The construction just described forms a back-gearing.

When the sliding hub 27 is moved downwards, the friction is locked in place and the pinion 36 is connected to turn with the bevel gear 19. When the sliding hub 27 is raised, the friction is disengaged, and the continued movement thereof locks the clutch teeth 29 and 30 together. When the parts take this position, power is transmitted by the pinion 31, gear 32, shaft 33, pinion 34 to gear 35, and as the gear 35 is secured to the hub 28 which is now locked to the upright shaft 22, the pinion 36 will be driven through its back gear train at a relatively slow and powerful speed compared with the speed when the power is taken directly up to the upright shaft 22.

I have found it to be a most advantageous construction to use a friction clutch when the pinion 36 is to be driven at its high speed, and a positive clutch, such as teeth 29 and 30, when the powerful back gearing is to be used, as I have found that a friction is best adapted for putting the parts in operation at the high speed, while when the powerful back train is used, the same can be put in mesh easily with a positive clutch, and a positive clutch is most desirable to take the heavy strain due to the increased leverage of gearing down.

The sliding hub 27 has a groove cut in the same, and engaging the same is a yoke 37 which can be actuated by a handle 38 pivoted to the drill-head, so that either train of gearing can be used as desired by the operator by simple manipulation of said handle 38.

It is also an advantageous construction to use two arms 25—25 to coöperate with the sliding tapered hub 27, as by having the bearing points of said arms diametrically opposed, all tendency of the same to cramp or slip on the shaft 22 is eliminated.

The driving pinion 36 engages a driving gear 39, the hub of which is journaled in a bearing formed in the upper part of the drill-head. The drill spindle 40 fits in this hub, and has the usual key engaging a key-way in

said hub. The drill spindle fits and turns in the usual feed-quill 41, which is fitted to slide up and down in a bearing formed at the lower part of the drill head. The feed quill 41 has a key-way cut therein fitting a key inserted in said bearing in the usual manner, so that the drill spindle can be raised and lowered in the customary way. The drill spindle may be counterbalanced by a weight 42 which is connected thereto by a chain trained over suitable guiding pulleys. The feed quill 41 has a feed rack 43, engaging which is the usual pinion (not shown). On the end of the shaft of this pinion is arranged a clutch 44 which is formed inside of a worm-wheel 45. Engaging this worm-wheel is a worm 46 mounted on a shaft which is provided at its lower end with the usual feed wheel 47. The upper end of this shaft is provided with a clutch 48 by which the worm can be connected or disconnected from the power feed shaft 49. The clutch 44 is provided with the usual operating handles 50, and the clutch 48 is provided with the usual operating connections 51. The details of these parts are not shown and described at length, as they form no part of this present invention, and as the operation of the same is well understood, and is as follows:—By pulling out and turning the handles 50, the drill-spindle can be quickly raised or lowered. By leaving the handles 50 in their normal position, and by turning the feed-wheel 47, the drill-spindle can be fed up or down accurately through the worm and worm-wheel. 100

By manipulating the operating connections 51, the clutch 48 can be thrown in or out as desired, so that the drill-spindle can be fed by power or disconnected from the power feed. The gearing and connections by which the said feed shaft 49 is driven forms an important part of this invention. It is necessary to have said feed shaft so geared that it can be driven at different speeds, so that the different feeds can be obtained for the drill. 110 In manufacturing drills in large quantities, it has been found desirable to arrange this gearing so that it can be assembled and put together on the bench separately from the drill-head, and then accurately and quickly 115 adjusted and fitted in position on the drill-head. This advantage is obtained by the following arrangement:—Keyed on the lower end of the hub of the driving gear 39 are two gears 52 and 53 from which power is taken for the feed gearing. On the side of the drill head D are arranged two planing spots 54 and 55, consisting as usual of raised surfaces planed off to the same level for the brackets 56 and 57 respectively. The bracket 56 is 120 provided with two bearings 58 and 59. The end of the feed shaft 49 is journaled in the outer of said bearings. An intermediate shaft 60 is journaled in the other bearing 58, and in the bracket 57. A hub 61 is formed 130

on the bracket 56 concentrically with the bearing 58. Fitting on this hub is a swinging bracket 62 which has a hub 63 at its end, journaled in which is a shaft 64. The feed shaft 49 has secured thereto a series of gears 65, 66, 67 and 68, which mesh with a series of pinions 69, 70, 71 and 72 loosely fitted on the lower end of the shaft 60. The lower end of the shaft 60 is bored out, and fitted in the same is a sliding shaft 73 which carries a spring-pressed key 74 which projects through a slot cut in the shaft 60. Each of the pinions on said shaft 60 is provided with a key-way into which the said key 74 can engage. 15 The shaft 73 is provided with a handle or button 75, and with a friction 76. A pin is arranged in the shaft 60 on each dividing line between the pinions, and the head of the key 74 is tapered as shown, so that as the 20 sliding shaft 73 is pulled down or pushed up, said key will ride over said pins. By this construction any one of the four pinions can be locked to the shaft 60.

A gear 77 is secured to the top of the 25 shaft 60 and meshes with a pinion 78 secured on the top of the shaft 64. On the lower end of the shaft 64 are loosely arranged two gears 79 and 80. The shaft 64 is bored out, and fitting in the same is a sliding shaft 30 81, which has a key 82 which projects out through a slot cut in the shaft 64. A handle or button is arranged on the end of the sliding shaft 81, and a suitable friction device 84 is provided for said sliding shaft. A pin is 35 arranged in the slot of the shaft 64 on the dividing line between the gears 79 and 80. By sliding the shaft up or down either gear 79 or 80 can be locked to the shaft 64. The gears 79 and 80 are meshed with the gears 52 40 and 53 secured on the hub of the driving gear 39. By this construction power is taken to operate the feed shaft 49 through either gears 52 and 79, or 53 and 80, as the case may be, to turn the shaft 64, and by pinion 78 and gear 45 77 to operate the shaft 60, and then by the pinion which is locked to the shaft 60 through its intermeshing gear to turn the feed shaft 49. This gearing for driving the feed shaft is comparatively complicated. It can be 50 best assembled and put together on the bench, but the difficulty has arisen in doing this that it is hard to fit this gearing after assembly to the drill-head. This difficulty is overcome by the arrangement of brackets 55 before described. After this gearing is assembled on the bench, the brackets 56 and 57 are secured on their respective planing spots, only one alinement being necessary, and that is to get the end of the feed shaft 60 60 49 properly in its clutch-head. After this has been done and said brackets secured in place, the swinging bracket 62 is turned and set so that the gears 79 and 80 will properly mesh with the gears 52 and 53. The swing- 65 ing bracket 62 is preferably split, and is pro-

vided with a tightening bolt 85 by which the same can be tightly clamped in adjusted position. A pin 86 is usually driven through a projecting wing on said bracket 62 to lock the swinging bracket additionally to the bracket 56 after the same has been adjusted in position, the hole for the pin being drilled after the gears are properly meshed. By this arrangement this feeding gearing which is properly proportioned for eight different speeds for the drill spindle can be quickly assembled on the bench, and can be rapidly and accurately put in position on the drill-head. This is a very important point in practice as it greatly expedites the manufacture. 70 75 80

The radial arm C is provided with the usual rack, meshing with which is the usual spiral pinion carried by the drill head and operated by the handle 87, whereby the 85 drill-head can be adjusted longitudinally of the radial arm.

By the constructions before described, the operator has the reversing mechanism, the back-gearing mechanism, the different arrangements of the feed, and the position of the drill longitudinally and radially at his command without leaving his position. 90

The details and arrangements of parts can be worked out in other ways to accomplish 95 the ends of my improvements without departing from the scope thereof as expressed in the claims.

Having thus fully described my invention, what I claim and desire to secure by Letters 100 Patent is:—

1. In drill construction, the combination of a drill spindle, a power driven hub, a shaft, means for transmitting power from the shaft to the spindle, means for gradually and frictionally connecting the hub with the shaft while the hub is rotated to drive the shaft directly from the hub at a high speed, means detachable from the shaft for transmitting power from the hub to the shaft at a slow speed, and means for connecting said power transmitting means positively with the shaft. 105 110 115

2. In drill construction, the combination of a drill spindle, a shaft, means for transmitting power from the shaft to the drill spindle, a power driven hub, a friction clutch for directly connecting said hub with the shaft, a second hub loose on said shaft, a back-gear train connecting said hubs, whereby power may be transmitted from the first hub to the second hub at a reduced speed, and means for simultaneously disconnecting said friction clutch from the first hub and connecting said second hub positively with the shaft. 120

3. In drill construction, the combination of a drill head having two planing spots, two brackets adapted to be attached to the planing spots, said brackets having bearings in alinement for a shaft, and one of said brack- 125 130

ets having a hub concentric with said bearings and a second bearing, and a swinging bracket centered on said hub.

4. A feed gearing comprising a removable bracket having a bearing, a power transmitting shaft fitted therein, a hub formed on said bracket concentric with said bearing, a swinging bracket fitted on said hub, a shaft journaled in the end of said swinging bracket and gearing between said shafts, whereby the parts may be assembled before the bracket is mounted in position on the machine.

5. A feed gearing comprising a removable bracket having a bearing, a power driven shaft fitted therein, a hub arranged on said bracket concentrically with said shaft, a swinging bracket fitted on said hub, a shaft journaled in said swinging bracket, gearing arranged between said shafts and means for locking the swinging bracket in adjusted position.

6. A feed gearing comprising a bracket provided with bearings, a power transmitting shaft and a feed shaft fitted in said bearings, a change speed gearing between said shafts, a hub formed on said bracket concentrically with one of said shafts, a swinging bracket fitted on said hub, a shaft journaled in the end of said swinging bracket gearing between the shaft in the end of said bracket and the shaft passing through said hub, and means for locking the swinging bracket in adjusted position.

7. In a feed gearing, the combination of a bracket, a feed shaft 49 journaled therein, a shaft 60 journaled therein, a change speed gearing arranged between said shafts 49 and 60, a hub 61 projecting from said bracket concentrically with said shaft 60, a swinging bracket 62 mounted on said hub, a shaft 64 journaled in said swinging bracket, and gearing between the shafts 60 and 64.

8. In a feed gearing, the combination of the bracket 56, the feed shaft 49 journaled therein, the shaft 60 journaled therein, a change speed gearing arranged between said shafts 49 and 60, a hub 61 projecting from said bracket concentrically with the shaft 60, a swinging bracket 62 fitted on said hub, a shaft 64 journaled in the end of said swinging bracket, gearing between the shafts 60 and 64, gears 79 and 80 loosely arranged on the shaft 64, connections whereby either gear 55 may be thrown into engagement with the shaft 64, driving gears 52 and 53 engaging gears 79 and 80, and means for locking the bracket 62 in position with gears 79 and 80 properly in mesh with the gears 52 and 53.

9. In a feed gearing, the combination of a bracket, a feed shaft journaled therein, a second shaft journaled in the bracket, a change speed gearing mounted between said shafts, a hub projecting from the bracket concentrically with the second shaft, a swinging

bracket fitted on said hub, a third shaft journaled in said swinging bracket, gearing between the second and third shafts, a plurality of gears loosely mounted on the third shaft, connections whereby either of the gears on the third shaft may be thrown into engagement with said shaft, driving gears engaging said gears on the third shaft, and means for locking said swinging bracket in position with said gears properly in mesh.

10. In a feed gearing, the combination of a bracket, a shaft journaled therein, a swinging bracket journaled on said first named bracket concentrically with said shaft, an additional shaft journaled in said swinging bracket, gearing between said shafts, gears loosely arranged on the additional shaft, connections whereby any of said gears may be thrown into engagement with said shaft, driving gears engaging said gears, and means for locking the swinging bracket in position with the gears properly in mesh.

11. A feed gearing for drills consisting of a bracket carrying a change speed gearing, and an adjustable bracket mounted thereon carrying part of said gearing and arranged so that the same can be adjusted without destroying the mesh of the gearing, whereby all of said gearing can be assembled on the bracket and then said bracket can be secured to the drill head and the adjustable bracket set to mesh the change speed gearing to the gearing carried by the drill head.

12. A feed gearing for drills comprising a bracket carrying a change speed gearing, an adjustable bracket mounted thereon carrying part of said gearing and arranged so that the same can be adjusted without affecting the mesh of said gearing, and means for locking said swinging bracket in adjusted position to the main bracket, whereby said bracket can be secured in place and the adjustable bracket adjusted and set to mesh the change speed gearing properly with the gearing carried by the drill head.

13. In a drilling machine, a bracket, a change speed gearing carried by said bracket, an adjustable bracket mounted on the first bracket, and a gear carried by the second bracket for driving said change speed gearing arranged so that the same can be adjusted or swung without destroying the mesh of the gearing, whereby said bracket can be secured to the drill-frame, and the adjustable bracket set to mesh the gear to the gear which is to drive the same.

14. In a drilling machine, the combination of a bracket having two integrally formed hubs, a change speed gearing arranged between said hubs, a swinging bracket concentrically mounted on one of said hubs, gearing carried by said swinging bracket, and means for locking this bracket in adjusted position.

15. The combination of a bracket having

two integrally formed hubs, a series of gears arranged between said hubs, a swinging bracket mounted on one of said hubs, means carried by said swinging bracket for transmitting power to the series of gears, and means for locking the swinging bracket in adjusted position.

In testimony whereof I have hereunto set my hand, in the presence of two subscribing witnesses.

ALBERT E. NEWTON.
